No. 880,609.

PATENTED MAR. 3, 1908.

W. WATTS.
MAIL CRANE.
APPLICATION FILED SEPT. 19, 1907.

UNITED STATES PATENT OFFICE.

WILLIAM WATTS, OF SPRING GROVE, ILLINOIS.

MAIL-CRANE.

No. 880,609.

Specification of Letters Patent.

Patented March 3, 1908.

Application filed September 19, 1907. Serial No. 393,670.

To all whom it may concern:

Be it known that I, WILLIAM WATTS, a citizen of the United States, residing at Spring Grove, in the county of McHenry and State of Illinois, have invented certain new and useful Improvements in Mail-Cranes; and I do hereby declare the following to be a full, clear, and exact description of the invention, such as will enable others skilled in the art to which it appertains to make and use the same.

This invention relates to cranes for receiving mail-bags when being delivered from moving trains; and it consists in the novel construction and combination of the parts hereinafter fully described and claimed.

In the drawings, Figure 1 is a side view of the crane. Fig. 2 is a plan view of the crane. Fig. 3 is a cross-section through one of the 15 roller bearings, taken on the line $x-x$ in Fig. 2, and drawn to a larger scale.

A is a post which is secured in the ground adjacent to the railroad track. Bearing rings B are secured to the post A, one above the 20 other and at a suitable distance apart, by means of brackets b and suitable bolts.

The crane jib is provided with two bearings C for engaging with the rings B, and these bearings are similar to each other in 30 structure. Each bearing C is formed of two similar parts provided with flanges c and bolts for securing them together one above the other. A channel D' is formed between the two said parts, and the bearing ring B is arranged in this channel.

D are rollers arranged between the rings B and C so as to form an anti-friction bearing of approved construction, which will permit the bearings C to revolve very freely on the 40 bearing rings.

E are two arms which project from the upper bearing C.

F are two inclined arms which are secured at their upper ends to the outer ends of the 45 arms E. The lower ends of the arms F are secured to the lower bearing C. The arms E and F constitute the jib of the crane.

One of the bearings C is provided with a 50 spring-actuated bolt or catch f of any approved construction which normally engages with a notch in the bearing ring B when the crane is substantially at a right angle to the track rails and in a position to receive a mail-bag from a train. This catch is for the purpose of preventing the accidental displacement of the crane jib by the wind, or other

similar cause, until the mail-bag has been received by the crane. This catch is constructed so that it is thrown out of action when the crane is spun around with the mail-bag and when it is necessary that the crane jib should revolve freely.

A spring f' engages with teeth t in the catch f, or it may engage with it by frictional contact, and this spring normally holds the catch in engagement with a notch b' in the ring B. When the crane jib is swung around forcibly the catch is automatically forced out of engagement with the notch, the said parts being suitably beveled, and the catch is then held out of engagement with the notch by the same spring f', so that the jib is free to be whirled around the post continuously without any check from the said catch.

G is a hook for receiving the mail-bag. This hook is reversible and it is provided with a shank g which is journaled in blocks h secured to the outer end portion of the pair of arms E. H is a slidable locking-plate which engages with the rectangular end portion i of the said shank and with the arms E. This plate can be slid out of engagement with the part i so that the hook can be turned over and reversed in the blocks h so as to receive a mail-bag from a train coming in the opposite 35 direction. The crane jib is free to revolve in each direction and the hook is placed in position by hand to suit the direction of the train.

The mail-bag is supported on the rapidly 90 moving train in any approved manner, and when received by the hook it causes the crane jib to spin rapidly around the supporting post. The crane jib with the mail-bag on it whirls around freely for a number of 95 revolutions and comes to rest slowly, so that the mail-bag is not injured in any way, and by means of this crane mail-bags can be delivered with safety from a train traveling at a high speed.

What I claim is:

1. In a mail-crane, the combination, with a supporting post, of a crane jib journaled to revolve freely in each direction on the said post, a reversible hook for the mail-bag 105 journaled at the end of the said jib, and a slidable locking device for holding the said hook in position.

2. In a mail-crane, the combination, with a supporting post, of two bearing rings secured one above the other to the said post, two bearings each formed of two parts se- 110

- cured together and forming an annular channel, antifriction devices arranged in the said channel and running on the said bearing rings, arms arranged in pairs and secured together at their outer ends and secured to the said bearings at their inner ends, and a hook for the mail-bag carried by the outer end portions of the said arms.
3. In a mail-crane, the combination, with a supporting post, of a crane jib journaled to whirl continuously around the said post, and

an automatically disengageable catch which normally checks the free movement of the said jib when the jib is in a position to receive a mail-bag.

15 In testimony whereof I have affixed my signature in the presence of two witnesses.

WILLIAM WATTS.

Witnesses:

Wm. RADEN,
NICHOLAS BLAKE.
